UNITED STATES PATENT OFFICE.

HARRY CRUTCHLEY, OF JERSEY CITY, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,142,800.

Specification of Letters Patent. Patented June 15, 1915.

Application filed June 11, 1910. Serial No. 566,282.

To all whom it may concern:

Be it known that I, HARRY CRUTCHLEY, a citizen of the United States, residing in Jersey City, in the county of Hudson and State of New Jersey, have invented certain new and useful Improvements in Type-Writing Machines, of which the following is a specification.

My invention relates to tabulating mechanisms for typewriting and other machines.

I provide a compound rack or plate having several rows of perforations extending parallel with the direction of feed of the carriage; column stops being adjustably mounted thereon, with their lower ends projecting through the perforations to engage a key-controlled counter-stop. By providing several racks and a separate key-controlled stop for each rack, the column stops can be adjusted for different columns. Certain of these column stops may also be arranged to permit decimal tabulating, said keys serving in this connection as decimal keys.

A further feature is the provision of an improved column-skipping mechanism of simple and efficient design. Several stops are arranged in as many different racks, said stops extending in an irregular diagonal line, across the series of racks, and corresponding with the first printing points in the several columns. The series of key-operated stops are used one for each rack, and each key co-operates only with the column stop in its associated rack, to enable the carriage to be skipped past one or more columns, depending upon the key depressed.

The invention provides simple and effective means for enabling a typewriting machine to be used to attain any two or more of the foregoing objects, that is to say, the machine may be used either for ordinary column tabulating work, or for decimal tabulating work, or for such work as requires the skipping or jumping of the carriage across one or more columns, or for any two or all of such purposes.

Other features and advantages will hereinafter appear.

In the accompanying drawings, Figure 1 is a perspective view, partly broken away, of the rack and key-controlled stops. Fig. 2 is a plan of the key-controlled stops and guide casing. Fig. 3 is a detail of one of

said key-controlled stops. Fig. 4 is a part 55 sectional end view showing the invention applied to an Underwood writing machine. Fig. 5 is a plan, showing the column stops on the compound rack, set to accord with the columnar arrangements of several different 60 forms. Fig. 6 is a similar view, showing the column stops set for column-skipping. Fig. 7 is a similar view, showing the column stops arranged for both decimal tabulating and column selecting. Fig. 8 is a perspective 65 view of a column stop holder.

The carriage 1 of an Underwood writing machine is mounted on the front and rear rails 2 and 3 of a frame 4, it being drawn in letter-spacing direction by a spring 5, and 70 provided with a rack 6 to mesh with the usual escapement-controlled pinion 7 to control the step-by-step movement of the carriage. Said rack 6 is carried by arms 8 pivoted to the carriage at 9.

Any of a set of tabulating keys 12 is depressed to cause its lever 12^a to elevate one of several stop-carrying rods 13 sliding in a holder or casing 14 at the rear of the machine, and provided with returning springs 80 13^a. Said levers are fulcrumed on a rod 12^b. Said rods 13 have shoulders 17, to lift a bar 18 fast on a shaft 19, to turn the latter and rock an arm 20, that is connected by a link 21 with one end of a releasing lever 22, pivoted at 23, whose opposite end disengages the rack 6 from the escapement pinion 7, to enable the spring 5 to drive the carriage 75 freely.

About simultaneously with the release of 90 the carriage 1, stop 24 on the top of rod 13 is projected into the path of a column step 25, depending from a table, plate or support 26, extending rearwardly from the carriage 1 over the key-controlled stops 24, to arrest 95 the carriage. Said table is provided with several rows of seats or holes 27, each row constituting a rack extending lengthwise of the carriage, (numbered as shown in the right in Fig. 1). Said table may be regarded as a compound or multiple rack. Each rack 27 contains about as many seats as there are letter-spaces in a line, there being as many rods 13 and stops 24 as there are racks, generally ten, although in some cases fewer 100 may be used. The rods are guided in grooves 28 in the casing 14.

The several key-controlled stops 24 lie

one behind another in a row transverse to the direction of movement of the carriage, so that each key-controlled stop co-operates only with those column stops (one or more), 5 which are mounted in the particular rack beneath which it is located. The upper ends of the rods 13, (except the first, 24^a), are bent or directed rearwardly as at 32, then laterally, as at 33, and then upwardly to 10 form the stops (see Figs. 1, 2 and 3), the bent arms 32, 33 of the successive rods increasing in length, from left to right in the drawings, so that the stops 24 may lie beneath their respective racks 27. The stop rods 13 and the operating keys 12 are arranged in rows extending in the direction of the carriage travel. The stops 24 may be otherwise formed and mounted and connected to the keys.

20 In Fig. 1, the stop 24 co-operating with the stops in rack No. 5, is shown projected into the path of the column stops 25 of said rack. Thus, the first key-controlled stop 24^a may be struck by the column stops 25 25 seated in the rack No. 1 on the table 26, and so on.

Each column stop is preferably in the form of a stud, (Fig. 1), one end 34 of which is reduced to fit into the seats in the 30 rack 27 and to depend below the rack, to engage the key-controlled stops; and being shouldered, as at 35, to rest on the top of the rack. The column stops are interchangeably mounted in any of the seats of the 35 racks. A scale 36 extending parallel with the racks 27, and corresponding to the usual letter-spacing scale on the front of the frame, enables the column stops 25 to be properly located.

40 In the usual tabulating work, the column stops 25 are seated along any one of the numbered racks or rows of seats, as that numbered 1 for instance, (Fig. 5), said stops being spaced at intervals equal to the distance between the first printing point in one column to that in the next column. The carriage being at the first column, the depression of that key 12 which co-operates with the column stops in rack No. 1, releases 45 the carriage from its letter-feeding mechanism, and throws the key-controlled stop 24^a into the path of the first of the series of column stops 25 to arrest the carriage at the first printing point in the second column; 50 and after the entry has been made, the depression of the same key projects its stop 24^a into the path of the second column stop in the same rack, to effect the arrest of the carriage at the first printing point in the 55 next column, and so on.

In case several blanks or forms, having different columnar arrangements, are to be filled out from time to time, the column stops in a second row, (as No. 2, Fig. 5), 60 may be adjusted to accord with the intervals

between the columns of the second printed blank, the stops in a third row (No. 3, Fig. 5), being arranged with regard to the column arrangement of a third blank, and so on. When any of the different blanks is being written, that particular key-controlled stop 24, which co-operates with the rack bearing the series of column stops that is set for the particular blank, is operated to jump the carriage from column to column. Thus loss of time incident to re-setting the stops for each different blank or form is avoided. The machine is capable of properly spacing the entries in as many forms as there are racks, but while ten racks are indicated in Fig. 5, it will be seen that the number can be reduced if desired. It will also be understood that the stops may be arranged on the several racks to accord with various columnar arrangements on different sections of the same printed form or blank, thereby facilitating the work of filling out said form or blank.

For decimal tabulating, the keys 12 are used as ordinary decimal keys. The column 90 stops 25 may be arranged in the seats in echelon across the compound rack 26 in one or more series (Fig. 7), each series corresponding with a separate column on the work sheet, each column stop in one series 95 lying one letter-space in advance of or behind the preceding or succeeding stop in the adjacent racks. In Fig. 7, for example, the stops are arranged in series of tens extending from any one of the seats in row No. 1 to row No. 10. The projection of the last key-controlled stop 24^b into the path of the column stop 25 of the series of decimal 100 arranged stops, in row No. 10, will arrest the carriage in position to write in one 105 column an amount comprising, say, seven digits, properly punctuated, and the column stop of said decimal arranged series (seated in rack No. 1), by co-operating with the first key-controlled stop 24^a, may be arranged to arrest the carriage at the proper 110 place in said column to print a decimal point. The intermediate column stops arrest the carriage at different points between the decimal and the seventh digit.

To facilitate the location and the insertion of the column stops in the racks 27 when it is desired to use the mechanism for decimal tabulating, a series of column stops 25^c may be fixed in a holder 37 (Fig. 8), the 115 lower ends of the column stops projecting below the holder to pass through a series of seats extending obliquely across the compound rack 26, to engage the key-controlled stops 24—24^a. The sides of the holder lie 120 about parallel with the series of stops 25^c to economize space, so that as many such holders can be employed side by side, (as at the left in Fig. 7), as desired.

The adjustment of the mechanism for col. 130

umn skipping is best shown in Fig. 6. One column stop only for each column may be employed. The carriage being in the first column, the operation of the first key-controlled stop 24^a will release and then arrest the carriage at the first printing point in the second column. In case no further entry is to be made in that line until the fourth column, however, the operation of the third key-controlled stop 24^c, which lies in the path of the column stop 25 for the fourth column only, will enable the carriage to skip from the first column to the printing point of the first character in said fourth column.

15 In Fig. 7, an arrangement of stops is shown illustrating one of the large number of purposes to which the invention can be adapted. The stops 25 for the first column are shown decimaly arranged (at the extreme right of the drawing), and when printing in this column, the stops 24 are used as decimal stops. Successive stops 25 are arranged diagonally across the compound rack to, enable the carriage to be skipped past one or more columns after the first column, the position of the carriage regarding the last two columns being controlled by two series of decimaly arranged stops on the compound rack. This device

25 may also be used for column skipping, since the keys are associated respectively with the several stops on said bar 37, and hence by depressing any desired key the carriage may be positioned by a corresponding stop on said bar. The invention is not limited to the form of bar 37 shown, nor to the special arrangement of stops thereon.

40 Variations may be resorted to within the scope of the invention, and portions of the improvements may be used without others.

Having thus described my invention, I claim:

1. In a typewriting machine having a power-driven carriage, a tabulating mechanism comprising means to release the carriage to enable the carriage to jump from column to column, and means to control the jump of the carriage when so released, said controlling means comprising a compound rack attached to the carriage, and having a number of rows of seats arranged about parallel to the line of movement of the carriage, column stops removably mounted in said seats according to the positions in the printing line at which the carriage is to be arrested, and selective key-operated stops, one for each row on the rack to project into the path of the stops of its particular row to arrest the rack and carriage; the key-operated stops having movement in a line substantially perpendicular to the rack and having offsets transverse to the rack and of different lengths so that each stop lies opposite its respective row.

65 2. In a typewriting machine having a

power-driven carriage, a tabulating mechanism comprising means to release the carriage to enable the carriage to jump from column to column, means to control the jump of the carriage when so released, said controlling means comprising a compound rack attached to the carriage, and having several rows of seats arranged about parallel to the line of movement of the carriage, column stops removably mounted in said seats, and selective key-operated rods, one for each of the rows on the compound rack, stops on the rods to project into the path of the column stops of its particular row to arrest the carriage; the stops having movement in a line substantially perpendicular to the rack and having offsets transverse to the rack and of different lengths to bring each stop opposite its respective row, and having other offsets of different lengths to bring the stop-engaging faces into alignment transversely of the rack.

3. In a typewriting machine, the combination with a frame and a power-driven carriage, of a tabulating mechanism comprising a series of key-controlled stops on the frame, a rack having several rows of seats extending about parallel with the direction of movement of the carriage, and a column stop holder in which are fixedly mounted several column stops in predetermined relation, said holder with its stops removably mounted on the rack to engage the key-controlled stops to arrest the carriage at any one of several printing points in a single column.

4. The combination with a carriage, of a tabulating mechanism comprising a set of keys and removable holders having stops, a set of counter-stops corresponding to said stops, whereby each stop can coöperate only with its associated counter-stop, keys to operate said counter-stops, and carriage releasing mechanism operable by said keys.

5. The combination of a carriage, a tabulating mechanism comprising a rack, stops adjustable thereon, a set of keys, counter-stops controlled by said keys; said rack having rows of seats for said stops, all of the seats in each row being at letter-space intervals, there being a key for each row and a sufficient number of rows to permit said keys to be employed for either column-skipping or decimal tabulating, at will, and removable holders having stops to coöperate with the respective counter-stops.

6. The combination of a carriage, a tabulating mechanism comprising a rack, stops adjustable thereon, a set of keys, and counter-stops controlled by said keys, said rack having rows of seats for said stops, all of the seats in each row being at letter-space intervals, there being at least one key for each row and a sufficient number of said rows and stops to permit said keys to be

employed for either column-skipping or decimal tabulating at will without varying the operated position of the stops.

7. The combination of a carriage, a tabulating mechanism comprising a rack fast on the carriage, stops adjustable thereon, a set of keys, counter-stops controlled by said keys, said rack having rows of seats for said stops, all of the seats in each row being at letter-space intervals, there being one key for each row and a sufficient number of said rows and stops to permit said keys to be employed for either column-skipping or decimal tabulating at will without providing more than one stop position for each stop and counter-stop, and carriage-releasing mechanism operable by the stop-setting strokes of said keys.

8. In a typewriting machine, the combination with a frame and a power-driven carriage, of a tabulating mechanism comprising a series of key-controlled stops on the frame, a rack having rows of seats extending substantially parallel with the direction of movement of the carriage, and a column stop holder having a plurality of column stops, said holder being adjustable to different columnar positions on the rack for co-action with the key-controlled stops, to arrest the carriage at any one of several printing points in the column for which said holder is set.

9. In a typewriting machine, the combination of a carriage, and means by which only columnar selection can be effected at one part of the carriage travel, and by which only denominational selection can be effected at another part of the carriage travel, and by which the position of the carriage in its travel from one side of the machine to the other determines automatically which kind of selection can be effected, said means comprising columnar devices, denominational devices, and arresting means coöperative therewith.

10. In a typewriting machine, the combination of a carriage; and tabulating mechanism including means by which a columnar selection only can be effected at one part of the travel of the carriage and a denominational selection only can be effected at another part of the travel of the carriage, and means for affording an adjustment of parts of the mechanism for varying the point in the travel of the carriage where the mechanism becomes inoperative for columnar selection and operative for denominational selection.

11. In a typewriting machine, the combination of a carriage; and denominational and column selecting tabulating mechanism including means by which said tabulating mechanism is necessarily operative as a denominational tabulator or as a column selec-

tor depending on the position of the carriage in its line of travel.

12. In a typewriting machine, the combination of a carriage; and denominational and column selecting mechanism including means by which said tabulating mechanism is necessarily operative at one time as a denominational tabulator and at another time as a column selector, and also including means for affording an adjustment of certain parts of said mechanism by which adjustment the tabulating mechanism may be made to operate first as a denominational tabulator and then as a column selector or vice versa.

13. In a typewriting machine, the combination of a carriage, a series of column stops, a stepped stop, means to engage both said column stops and said stepped stop, and keys operatively connected to said engaging means.

14. In a typewriting machine and tabulating mechanism, the combination of tabulator keys, and means whereby said keys are automatically rendered operative or effective at one time as column selecting keys and at another time as denomination selecting keys, said means comprising a carriage, a series of column stops, a stepped stop, and arresting means controlled by said keys and coöperative with said column stops and said stepped stop.

15. In a typewriting machine and tabulating mechanism, the combination of tabulator keys, and means whereby said keys are automatically rendered operative or effective at one time as column selecting keys and at another time as denomination selecting keys, the position of the carriage in its line of travel determining whether the keys are operative for denominational selection or for column selection, said means comprising a carriage, a series of column stops movable with the carriage, a stepped stop moved by the carriage, and arresting means controlled by said keys and coöperative with said column stops and with said stepped stop, the construction and arrangement of the parts being such that said arresting means may be brought into coöperative relation with one of said column stops but not with said stepped stop during one portion of the travel of the carriage and may be brought into coöperative relation with said stepped stop but not with said column stops at another portion of the travel of the carriage.

16. In a typewriting machine, the combination of a carriage; and tabulator mechanism comprising traveling stops of two different characters, and key controlled means coöperative with traveling stops of one character at one portion only of the travel of the carriage for column selection and co-

operative with traveling stops of a different character at another portion only of the travel of the carriage for denominational selection.

5. 17. In a typewriting machine, the combination of a carriage; and tabulating mechanism including means by which said mechanism is operative successively a predetermined number of times during the writing

of a single line as a column selector only and 10 is thereafter operative during the writing of the same line as a denominational selector only, the change of conditions taking place automatically.
